UNITED STATES PATENT OFFICE.

LOUIS J. REMMELE, OF NEWARK, NEW JERSEY, ASSIGNOR OF ONE-HALF TO AMELIA MAIER, OF NEWARK, NEW JERSEY.

REED-BENDING AND TUFT-FORMING APPARATUS.

Application filed November 19, 1926. Serial No. 149,332.

This invention relates, generally, to improvements in rotary brooms or brushes of the type generally used with street-sweepers, track-cleaning apparatuses, or the like; and the present invention has reference, more particularly, to a novel device or apparatus for the production of reed-sections, and the application of such reed-sections by means of the said device or apparatus to a holding frame of the character set forth in my former Patent No. 1,309,695, issued July 18, 1919, or to other suitably constructed reed-receiving and holding frames.

The present invention has for its principal object, the production of a novel and simply constructed device for folding reeds to provide brush-sections or tufts, and for arranging such brush-sections or tufts in their properly assembled positions within a brush-frame of the character specified in said above-mentioned Letters-Patent, or within any other suitably constructed brush-frame with which said brush-sections or tufts may be employed.

The invention has for a further object to provide a device or apparatus into which the brush material, such as reeds, is supplied in a straightened condition, the device being provided with a folding means for folding the reeds in the middle, and then locking the bunch of folded reeds, to provide a brush-section or tuft, which is then inserted in the brush-frame, while still held by the folding device or apparatus, for attachment of the brush-section or tuft to the brush-frame, by means of a retaining bar or rod, after which the folding device or apparatus is opened up and removed from the brush-frame, for the folding of another bunch of reeds and the attachment of the produced brush-section or tuft to the brush-frame in its position adjacent to the position of the previously placed brush-section or tuft, and to be also held in place by the said retaining bar or rod.

Other objects of the present invention not at this time more particularly enumerated will be understood from the following detailed description of the same.

With the various objects of the present invention in view, the present invention consists, primarily, in the novel reed-folding and brush-section producing device or apparatus hereinafter more fully set forth; and, the said invention consists, further

more, in the novel arrangements and combinations of the various devices and parts, as well as in the details of the construction of the said parts, all of which will be more fully described in the following specification, and then finally embodied in the clauses of the claims which are appended to and which form an essential part of the said specification.

A practical embodiment of the invention is represented in the accompanying drawings, in the several figures of which similar characters of reference are employed to indicate corresponding parts.

In the said drawings, Figure 1 is a view, partly in side elevation and partly in section of the main reed-folding device or apparatus, showing the movable parts thereof in their normal initial positions, said view illustrating in connection therewith a number of reeds placed in position, prior to locking or holding the reeds in position within said device or apparatus. Figure 2 is a side elevation of the said main folding device or apparatus, with the inserted reeds held in position within the device or apparatus, prior to the bending or folding of the reeds in the middle; and Figure 3 is a top or plan view of the several parts of the device or apparatus as represented in said Figure 2.

Figure 4 is a side elevation of the reed-folding device or apparatus, with the reeds held in position therein, but shown reversed from the positions indicated in Figures 1 and 2, and the said view illustrating in connection therewith a supplemental reed-folding frame for folding the extending portions of the reeds over and upon the previously clamped portions of the reeds within the main folding device or apparatus; and Figure 5 is a similar view, showing the said supplemental reed-folding frame, rotated over and down upon the said main reed-folding device or apparatus.

Figure 6 is a side elevation of the said main reed-folding device and of the said supplemental reed-folding frame, showing the reeds, in the form of a tuft, clamped within the main folding device or apparatus, and with the supplemental frame shown again in its removed position from above the said main reed-folding device or apparatus; and Figure 7 is a similar view of the device and parts, as represented in said Figure 6, but showing the main reed-folding device

or apparatus, with the reed-tuft therein, lifted from the bench or table upon which it was previously placed, for insertion of the tuft by means of the said device or apparatus in a brush-frame.

Figure 8 is a top or plan view of the devices and parts, when represented in the positions indicated in said Figure 6; and Figure 9 is a transverse vertical section, on an enlarged scale, said section being taken on line 9—9 in Figure 4, looking in the direction of the arrow α , with the reed-tuft omitted from said view.

Figure 10 is a view of the main folding device or apparatus, with the reed-tuft held therein, illustrating the manner of inserting the tuft into the brush-frame, portions of said latter frame being indicated in dotted outline.

Similar characters of reference are employed in all of the said above described views, to indicate corresponding parts.

Referring now to the several figures of the drawings, the reference-character 1 indicates, in section, a fragmentary portion of a suitable bench, table, or support, upon which the main reed-folding device or apparatus may be placed, for the purposes hereinafter more fully set forth.

The above-mentioned main folding device or apparatus comprises a reed-receiving frame, consisting essentially of a bed-plate 2 formed with longitudinally extending side-walls 3 and 4, and a laterally extending end-member 5 at the one end of the said bed-plate, substantially as shown in Figures 1 and 3 of the drawings. At one end, the said bed-plate is also provided with standards or legs, as 7, and at its other end the side-walls 3 and 4 are provided upon their outer faces with outwardly projecting members 8 with each of which is connected and extend in opposite directions from said members 8, other members, as 9 and 10, the said members 10 also serving, ordinarily, as standards or supports for the device, as will be evident. As shown, the members 9 are provided with receiving slots 11 into which project suitably shaped retaining lugs or fingers 12, the said members 10 being cut away, as at 13, and being likewise formed with suitably shaped retaining lugs or fingers 14.

The said members 10 are further provided with A-shaped, or other suitably shaped receiving openings 15, and extending from the said bed-plate 2, in suitable locations, are lugs 16 preferably V-shape, as shown, but which may be otherwise shaped, if desired.

Extending laterally across the end of the bed-plate 2, which is partially closed by the end-member 5, is a plate-like extension 17, provided with upwardly projecting pintle-receiving ears 18. Connected with said extension 17 is a suitably shaped bar 19 which terminates in a suitably shaped gripping

member or handle, as 20. Pivotedly connected with said ears 18, by means of pivot-bolts or pins 21, are arms 22 to the outer end-portions of which are pivotally connected by means of pivot-bolts or pins 23, a second set 70

of arms 24 which are connected at the opposite end-portions by a laterally extending locking rod or bar 25, adapted to enter the previously mentioned receiving slots 11 and to enter into holding or locked engagement 75 with the retaining lugs or fingers 12. Also pivotally connected with the said arms 24, by means of pivot-bolts or pins 26, and located between said arms 24, is a suitably formed handle or gripping element, as 27, for moving the said locking rod or bar 25, into or out of engagement with the said lugs or fingers 12, as will be evident. Suitably connected with, and extending from the opposite ends of the side-walls 3 and 4, are elements 80 28 and 29 provided with receiving openings, as 30. Connected with and extending from one of said members 8 is an arm 31, the free end-portion 32 of which terminates at one side of the opening 30; as shown in the several figures of the drawings, the said end-portion 32 providing a stop for the purposes 90 to be hereinafter more fully set forth. Pivotally attached to the previously mentioned standards or legs 7 by means of pivot-bolts 95 or pins 33 is another pair of arms 34, and pivotally connected with the outer ends of said arms 34, by means of pivot-bolts or pins 35, are other arms 36 which are connected at their opposite end-portions by a laterally extending locking bar or rod 37, adapted to enter into holding or locked engagement with the previously mentioned lugs or fingers 14.

Also pivotally connected with the said arms 36, by means of pivot-bolts or pins 38, is a 100 suitably formed handle or gripping element, as 39, for moving the said locking bar or rod 37 into or out of engagement with the said lugs or fingers 14, as will be evident. Extending rearwardly from the members 8 110 of the above-described main folding device or apparatus are a pair of resilient holding tongues or lugs 40, the purpose of which will be presently more fully set forth.

In addition with the herein-above described main device or apparatus, I prefer to employ another bench, table, or suitable support, as 41, to which is secured by means of bolts 42, or otherwise a pair of suitably formed blocks 43, each block being provided with a recessed portion, as 44, as will be more fully understood from an inspection of Figures 4, 5, 6, 7 and 8 of the drawings. These blocks 43, as will be seen more particularly from Figure 8 of the drawings, are connected at one end by a laterally extending portion 45, against which the hereinabove described main folding device, with the reeds clamped therein in their non-folded positions, abuts, when said device in its 120 125 130

reversed position is shoved between the two blocks 43, thus bringing the several devices and parts in the relative positions, represented in Figure 4 of the drawings.

5 The previously mentioned reed-folding frame, as will be seen from said Figures 4, 5, 6, 7 and 8 of the drawings, comprises a pair of suitably spaced brackets 46, secured to said table or bench 41 by means of 10 bolts 47, or other suitable fastening means. The frame itself consists of a pair of longitudinally extending members 48, formed at one end with angular portions 49, which are pivotally connected by means of pivot- 15 bolts or pins 50 with the said brackets 46, the said members 48, at their opposite ends, being connected by means of rod or bar 51 which serves as a handle or lifting element for the purposes to be presently more fully 20 described. As shown, the said members 48, in suitable locations are provided with supporting members or legs, as 52, and with laterally extending lugs 53 and 54, which are suitably perforated, as shown, so as to pro- 25 vide guides, for movable arrangement with the said guides of suitably shaped bars 55 and spring-supported rods 56 connected therewith, substantially as shown in Figure 9 of the drawings. The said bars 55 are of 30 such lengths that their end-portions 57 will provide guiding stays, between which the extending portions of the reeds, see Figure 4 of the drawings, are arranged so as to prevent lateral spreading of the bunched reeds, 35 as will be evident. The said members 48 are further provided with suitably formed projections 58, connected by a laterally extending bending element or bar, as 59, and with a set of V-shaped projections 60, adapt- 40 ed when in the position represented in Figure 5 of the drawings to enter the hereinbefore mentioned A-shaped receiving openings 15, as shown in said figure.

Having in the foregoing described the general arrangements and constructions of the several devices and parts comprising my novel reed-tuft forming and bending device or apparatus, I will now briefly set forth the manner of bending a bunch of assembled reeds, to provide a tuft, and the manner of securing the tuft, by means of a rod 61, or similar securing means, in its position between the members 62 of a rotary brush-frame, or the like.

55 Referring to Figure 1 of the drawings, the requisite number of reeds 63 is arranged within the reed-receiving frame, with the end-portions 64 of the reeds projecting from the end of the said frame, substantially as shown in said figure. The end-portions of the bunch of bristles located upon the bed-plate 2 and between the side-walls 3 and 4, are now securely clamped by means of the locking rod or bar 25 in fixed positions 60 within the said frame, by moving the arms

22 and 24 from their positions represented in said Figure 1 to the positions shown in Figures 2 and 3 of the drawings, the rod or bar 25 having entered the receiving slots 11 and being brought into holding engagement with the retaining lugs or fingers 12. 70

This much of the device or apparatus is now lifted from the table or bench 1 and in its reversed relation inserted between the two blocks 43 upon the table or bench 41, substantially as shown in Figure 4 of the drawings, with the projecting end-portions 64 of the bristles arranged between the angular portions 49 of the frame-members 48, and between the guiding-stays 57, and resting also upon the laterally extending bending element or bar 59. By rotation of the bending frame directly over the main reed-receiving frame, arranged between the blocks 43, as indicated in Figure 5 of the drawings, the reeds are also bent in their middle, so as to produce a reed-tuft, as shown in said last-mentioned figure. When the various devices and parts are in the relative positions represented in said Figure 5, the arms 34 and 36 are moved from the positions shown in Figure 4 to the positions indicated in said Figure 5, with the locking rod or bar 37 having entered the receiving slots 13 and being brought into holding engagement with the retaining lugs or fingers 14, as clearly indicated in said Figure 5. This having been accomplished, the reed folding frame, comprising the members 48, is again turned back into its normal position indicated in Figures 6 and 7 of the drawings, to permit of the removal of the reed-tuft carrying frame from between the blocks 43, as shown in said Figure 7. As indicated in Figure 10 of the drawings, the folded portion of the reed-tuft, with the main folding device in which the tuft is clamped, as hereinabove described, is then inserted in the brush-frame, between two of its members 62, and secured in position by means of the usual rod 61, substantially as illustrated in said Figure 10. By means of the gripping members or handles 27 and 39, the various clamping devices are thereupon disengaged to permit of the main folding device to be removed from the tuft fixed in place in the brush-frame, for the production of another reed-tuft and for securing the latter in its fixed position in the brush-frame, adjacent to the previously secured reed-tuft, as indicated in said Figure 10 of the drawings. 100

105 Having in the foregoing described the general arrangements and constructions of the several devices and parts comprising my novel reed-tuft forming and bending device or apparatus, I will now briefly set forth the manner of bending a bunch of assembled reeds, to provide a tuft, and the manner of securing the tuft, by means of a rod 61, or similar securing means, in its position between the members 62 of a rotary brush-frame, or the like.

110 Referring to Figure 1 of the drawings, the requisite number of reeds 63 is arranged within the reed-receiving frame, with the end-portions 64 of the reeds projecting from the end of the said frame, substantially as shown in said figure. The end-portions of the bunch of bristles located upon the bed-plate 2 and between the side-walls 3 and 4, are now securely clamped by means of the locking rod or bar 25 in fixed positions 115 within the said frame, by moving the arms

120 Of course, I am aware, that changes may be made in the general arrangements and combinations of the various devices and parts, as well as in the details of the construction of the said parts, as set forth in the foregoing specification, and as defined in the clauses of the claims which are appended thereto. Hence, I do not limit my present invention to the exact arrangements and 125

combinations of the several devices and parts as described in the said specification, nor do I confine myself to the exact details of the construction of the said parts, as illustrated in the accompanying drawings.

I claim:

1. In a reed-tuft forming device, a main frame adapted to receive a quantity of straight reeds, so that portions of the reeds will project from an end of said frame, means for clamping the inserted portions of the reeds in said frame, a supplementary frame for bending the projecting portions of the reeds, and additional clamping means connected with said main frame, for clamping the bent portions of the reeds in position within the main frame so as to produce a tuft.
2. In a reed-tuft forming device, a main frame adapted to receive a quantity of straight reeds, so that portions of the reeds will project from an end of said frame, said frame comprising a bed-plate provided with longitudinally extending side-walls and a connecting end-wall, said side-walls being provided with receiving slots and retaining fingers, and means connected with said bed-plate for clamping the inserted portions of the reeds in said frame, comprising a plate-like extension, pintle-receiving ears carried by said extension, a pair of arms pivotally connected with said ears, a second set of arms pivotally connected with said first-mentioned arms, and a locking rod between said second-mentioned arms adapted to enter said receiving slots and engage said retaining fingers for clamping the reeds in position.
3. In a reed-tuft forming device, a main frame adapted to receive a quantity of straight reeds, so that portions of the reeds will project from an end of said frame, said frame comprising a bed-plate provided with longitudinally extending side-walls and a connecting end-wall, said side-walls being provided with receiving slots and retaining fingers, and means connected with said bed-plate for clamping the inserted portions of the reeds in said frame, comprising a plate-like extension, pintle-receiving ears carried by said extension, a pair of arms pivotally connected with said ears, a second set of arms pivotally connected with said first-mentioned arms, and a locking rod between said second-mentioned arms adapted to enter said receiving slots and engage said retaining fingers for clamping the reeds in position, combined with a supplementary frame for bending the projecting portions of the reeds, and an additional clamping means connected with said main frame, for clamping the bent portions of the reeds in position within said main frame so as to produce a tuft.
4. In a reed-tuft forming device, a main

frame adapted to receive a quantity of straight reeds, so that portions of the reeds will project from an end of said frame, said frame comprising a bed-plate provided with longitudinally extending side-walls and a connecting end-wall, said side-walls being provided with receiving slots and retaining fingers, and means connected with said bed-plate for clamping the inserted portions of the reeds in said frame, comprising a plate-like extension, pintle-receiving ears carried by said extension, a pair of arms pivotally connected with said ears, a second set of arms pivotally connected with said first-mentioned arms, and a locking rod between said second-mentioned arms adapted to enter said receiving slots and engage said retaining fingers for clamping the reeds in position, supporting members extending from said bed-plate, one set of said supporting members being provided with receiving slots and retaining fingers, and a clamping means pivotally connected with the other set of said supporting members, consisting of a pair of arms, a second set of arms pivotally connected with the said first-mentioned arms, and a locking rod between said last-mentioned second set of arms adapted to enter the receiving slots in the above-mentioned supporting members and engage the retaining fingers of said supporting members.

5. In a reed-tuft forming device, a main frame adapted to receive a quantity of straight reeds, so that portions of the reeds will project from an end of said frame, said frame comprising a bed-plate provided with longitudinally extending side-walls and a connecting end-wall, said side-walls being provided with receiving slots and retaining fingers, and means connected with said bed-plate for clamping the inserted portions of the reeds in said frame, comprising a plate-like extension, pintle-receiving ears carried by said extension, a pair of arms pivotally connected with said ears, a second set of arms pivotally connected with said first-mentioned arms, and a locking rod between said second-mentioned arms adapted to enter said receiving slots and engage said retaining fingers for clamping the reeds in position, supporting members extending from said bed-plate, one set of said supporting members being provided with receiving slots and retaining fingers, and a clamping means pivotally connected with the other set of said supporting members, consisting of a pair of arms, a second set of arms pivotally connected with the said first-mentioned arms, and a locking rod between said last-mentioned second set of arms adapted to enter the receiving slots in the above-mentioned supporting members and engage the retaining fingers of said supporting members, combined with a supplementary frame for bending the projecting portions of the reeds prior

to clamping said bent reed-portions within said main frame.

6. In a reed-tuft forming device, a main frame adapted to receive a quantity of straight reeds, so that portions of the reeds will project from an end of said frame, said frame comprising a bed-plate provided with longitudinally extending side-walls and a connecting end-wall, said side-walls being provided with receiving slots and retaining fingers, and means connected with said bed-plate for clamping the inserted portions of the reeds in said frame, comprising a plate-like extension, pintle-receiving ears carried by said extension, a pair of arms pivotally connected with said ears, a second set of arms pivotally connected with said first-mentioned arms, and a locking rod between said second-mentioned arms adapted to enter said receiving slots and engage said retaining fingers for clamping the reeds in position, combined with a supplementary frame for bending the projecting portions of the reeds, and an additional clamping means connected with said main frame, for clamping the bent portions of the reeds in position within said main frame so as to produce a tuft, said supplementary frame comprising a pair of brackets, longitudinally extending members pivotally connected with said brackets, a lifting bar connecting the free end-portions of said longitudinally extending members, and a bending element connected with and extending laterally between said members.

7. In a reed-tuft forming device, a main frame adapted to receive a quantity of straight reeds, so that portions of the reeds will project from an end of said frame, said frame comprising a bed-plate provided with longitudinally extending side-walls and a connecting end-wall, said side-walls being provided with receiving slots and retaining fingers, and means connected with said bed-plate for clamping the inserted portions of the reeds in said frame, comprising a plate-like extension, pintle-receiving ears carried by said extension, a pair of arms pivotally connected with said ears, a second set of arms pivotally connected with said first-mentioned arms, and a locking rod between said second-mentioned arms adapted to enter said receiving slots and engage said retaining fingers for clamping the reeds in position, supporting members extending from said bed-plate, one set of said supporting members being provided with receiving slots and retaining fingers, and a clamping means pivotally connected with the other set of said supporting members, consisting of a pair of arms, a second set of arms pivotally connected with the said first-mentioned arms, and a locking rod between said last-mentioned second set of arms adapted to enter the receiving slots in the above-men-

tioned supporting members and engage the retaining fingers of said supporting members, combined with a supplementary frame for bending the projecting portions of the reeds prior to clamping said bent reed-portions within said main frame, said supplementary frame comprising a pair of brackets, longitudinally extending members pivotally connected with said brackets, a lifting bar connecting the free end-portions of said longitudinally extending members, and a bending element connected with and extending laterally between said members.

8. The herein-described reed-tuft forming device comprising a bed-plate provided with longitudinally extending side-walls and a connecting end-wall, said device being provided at opposite sides of the bed plate at the end near said end-wall with a pair of independently acting reed-clamping means.

9. The herein-described reed-tuft forming device comprising a bed-plate provided with longitudinally extending side-walls and a connecting end-wall, said device being provided at the end near said end-wall at opposite sides of the bed-plate with a pair of independently acting reed-clamping means, each clamping means consisting of two sets of pivotally connected arms, and a locking rod between one set of the arms of each clamping means, and the said device being provided with receiving slots and retaining fingers for entrance of the respective locking rods into the respective slots and for engagement with the respective retaining fingers.

10. The herein-described reed-tuft forming device comprising a bed-plate provided with longitudinally extending side-walls and a connecting end-wall, said device being provided at the end near said end-wall at opposite sides of the bed-plate with a pair of independently acting reed-clamping means, each clamping means consisting of two sets of pivotally connected arms, and a locking rod between one set of the arms of each clamping means, and the said device being provided with receiving slots and retaining fingers for entrance of the respective locking rods into the respective slots and for engagement with the respective retaining fingers, and a gripping or lifting element pivotally connected with one set of the arms of each clamping means.

11. The herein-described reed-bending frame for use in end to end alignment with a reed-tuft forming device, comprising a pair of fixed brackets, longitudinally extending laterally spaced members pivotally connected with said brackets, a hand grip connected between the free end-portions of said longitudinally extending members, a reed engaging and bending element connected with and extending laterally between said longitudinally extending members, guiding stays slidably connected with said longitu-

- dinally extending members for relative movement at right angles thereto in vertical plane, and spring means for projecting said stays downwardly when the latter members are raised.
12. The herein-described reed-bending frame for use in end to end alignment with a reed tuft forming device, comprising a pair of fixed brackets, longitudinally extending laterally spaced members pivotally connected with said brackets, a hand grip connected between the free end portions of said longitudinally extending members, a reed engaging and bending element connected with and extending laterally between said longitudinally
- extending members, V-shaped positioning projections extending from said longitudinally extending members in the plane thereof but at right angles thereto, guiding stays slidably connected with said longitudinally extending members for relative movement at right angles thereto in vertical plane, and spring means for projecting said stays downwardly when the latter members are raised. 20
- 25
- In testimony that I claim the invention set forth above I have hereunto set my hand this 18th day of November, 1926.

LOUIS J. REMMELE.
